COLLAPSIBLE CHAIR

Filed April 7, 1933

WITNESS:

UNITED STATES PATENT OFFICE

2,006,823

COLLAPSIBLE CHAIR

Albert Beeskow, New York, N. Y.

Application April 7, 1933, Serial No. 664,990

1 Claim. (Cl. 155—117)

This invention relates to collapsible chairs and it has for one of its objects the provision of a chair which may be collapsed or folded into a small space.

5 The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not 10 affect the spirit of the invention nor exceed the scope thereof as expressed in the appended claim.

In the drawing:

Fig. 1 is a side elevation of my improved collapsible chair.

20 Fig. 2 is a plan view of a locking construction employed in the chair.

Fig. 3 is a section on line 3—3 of Fig. 2.

Fig. 4 is a plan view of another connection employed in my invention; and

25 Fig. 5 is a view taken on line 5—5 of Fig. 4.

Referring to the drawing for a more detailed description thereof, the chair comprises frames A and B pivotally connected at 1. Frame A consists of a forward and upper part A1 and a rear 30 and lower part A2, the latter being connected to the former by sleeves 8 in which the frame part A2 is slidable so that the latter part of the frame A may be moved into the part A1. Said sleeves are secured to the part A1 of the frame A and 35 have forward and rear slots 8a and 8b, respectively, formed in their inner faces, the rear slots 8b being provided to accommodate the cross-piece 9 of the frame part A2 when the latter part of the frame is collapsed into the forward and upper 40 part A1 of the frame A. The forward recesses 8a are provided to accommodate the ends of a cross-piece 10 which forms the forward end of the frame part A2, the engagement of the cross-piece 10 in the recesses 8a locks the frame parts 45 A1 and A2 together. The frame B comprises a lower frame portion B1 and an upper frame portion B2 which are pivotally connected at 11 and 50 which are locked at their pivotal points by means of members 12 swingably connected on pins 13 to the upper portion B2 of the frame B. Said members 12 have slots 14 so that they may be pushed upwardly onto frame part B2, the pins 13 remaining in the slots 14, it being necessary to 55 push back the swingable members 12 when the frame parts B1 and B2 are to be collapsed. Said members 12 are punched to provide detents 15

which snap into notches 16 formed in the frame portion B1 and thereby lock together the frame parts B1 and B2.

A brace 17 is pivotally connected at 18 to the frame part B2 and is adapted to engage any one of the recesses 18 formed in the frame member A2. A canopy 19 is pivotally connected to the top of the frame part B2 and may be held in adjusted position by means of a fastening element 20. A sheet of flexible material 21 is secured to the cross-piece 22 of the frame part B2 and is also fastened to the cross-piece 23 of the frame part A1 and forms the back and the seat of the chair. The frame A is within the frame B and the brace is pivotally secured to the outer sides 15 of the frame B.

When collapsed, the frame part A2 is within frame part A1 and both of these are within frame part B1, while frame B2 is folded back on frame part B1, the brace 17 is swung over the top of frame part B2 and is outside of B1, and the canopy 19 rests on B2.

What is claimed is:

A collapsible chair comprising a first frame including members functioning as back posts and 25 front legs, a second frame within said first frame and pivotally connected thereto, said second frame including slidably connected front and rear parts of which the latter functions as rear legs, flexible material secured to the top of said first 30 frame and to the front of said second frame and forming the seat and the back of the chair, said first frame including upper and lower hinged parts adapted to be swung one onto the other, and a brace pivotally connected to said first frame 35 and engaging said second frame, and means for locking together the hinged parts of said first frame, said locking means comprising members pivotally secured to one of the parts of the first frame and slidably relative to that part and having 40 detents engaging notches in the other part of the same frame, sleeves secured to the front part of the second frame, the rear part of the second frame including side members and front and rear cross pieces connecting the side members adjacent their ends, said side members passing thru and being slidable in said sleeves, the latter having front and rear slots at the ends of their inner faces, the front slots being adapted to receive the end portions of the front cross piece 50 when the parts of the second frame are in extended relation and the rear slots of the sleeves being adapted to receive the end portions of the rear cross piece when the parts of the second frame are in relatively collapsed position. 55

ALBERT BEESKOW.
